Inventor:
Charles R. Hultgren,
By Dyrup & Smith, Sc., Chittenden, Vt.,
Attest,

UNITED STATES PATENT OFFICE.

CHARLES R. HULTGREN, OF CHICAGO, ILLINOIS, ASSIGNOR TO S. KARPEN & BROS.,
OF CHICAGO, ILLINOIS, A CORPORATION OF WEST VIRGINIA.

UPHOLSTERY CONSTRUCTION.

Application filed December 17, 1923. Serial No. 681,121.

This invention relates particularly to spring construction employed in upholstery work; and the primary object is to provide an improved construction, enabling upholstery to be provided with an improved "spring edge" in a simple and expeditious manner at a small cost.

The invention is illustrated in its preferred embodiment in the accompanying drawings, in which—

Fig. 1 represents a broken plan view of an upholstered frame, portions of the upholstery fabric being removed to expose the spring work; Fig. 2, a broken edge elevational view of the structure shown in Fig. 1; Fig. 3, a plan view of a clip employed for connecting with the end rings of the marginal roll of upholstery springs, a marginal wire and a flexible edge-roll of relatively large diameter; Fig. 4, a broken lower side view illustrating the connection between an end ring of one of the upholstery springs and the marginal wire before the edge-roll has been secured in position; Fig. 5, a sectional view taken as indicated at line 5 of Fig. 1; and Fig. 6, an enlarged broken sectional view taken as indicated at line 6 of Fig. 1.

In the construction illustrated, A represents a frame upon which is mounted rows of upholstery springs B; C a marginal wire disposed adjacent the outer portions of the marginal row of springs; D, an edge-roll disposed adjacent said marginal wire; E, clips connecting said marginal wire, said edge-roll, and the end rings of the upholstery spring; and F, a pad or cushion surmounting the spring structure.

In the illustration given, the frame A comprises longitudinal members 1, end members 2, and cross rods 3, the latter supporting the upholstery springs in a well known manner.

The end rings 4 of the springs are suitably tied together and to the frame by means of ties 5. The end members 2 of the frame, in the illustration given, have their upper surfaces disposed some distance above the upper surfaces of the longitudinal frame members 1. The marginal wire or rod C is shown secured to the end member 2 of the frame by means of staples 6. The longi-

tudinal portion of the rod C is disposed adjacent the outer portion of the end rings 4 of the marginal row of springs. 55

The edge-roll D is of flexible material and preferably several times the diameter of the marginal wire or rod C. The member D preferably surmounts the marginal rod C.

The clips E serve to secure the edge-roll 60 D and the marginal wire C together and also to secure these members to the tops of the marginal rows of springs. These clips may be stamped from sheet metal in the form shown in Fig. 3. In this form, the clip comprises a body portion 7 provided at each end portion with two short lateral arms 7^a, and at an intermediate portion with a short lateral arm 7^b, opposite to which is a long lateral arm 7^c. In applying the clip, 70 the arms 7^a are bent downwardly and clinched beneath the marginal wire and the end ring 4, and the intermediate arm 7^b is also clinched beneath the end ring 4.

After the marginal wire C has been applied, the edge-roll D is placed in position, and the end portions, in the construction illustrated, are secured, by tacks 8, to the end members 2 of the frame. 75

The long arms 7^c of the clips are then 80 curved upwardly and about the edge-roll, as illustrated in Fig. 5. Thus, the arms 7^c become, in effect, rings which embrace and grip the edge-roll and hold it in a position 85 surmounting the marginal wire C which preferably is substantially tangential to the rings of the marginal row of springs.

The cushion or covering F may be of any suitable form. In the illustration given, it comprises an envelope 9 filled with suitable 90 padding material 10 such as cotton, moss, or hair. The envelope is provided with an inner marginal flap 11 and an outer marginal flap 12. The inner flap is extended over the edge-roll, or pad-roll D, and the fabric 95 is caused to practically envelop the edge-roll, and is secured in position on the edge-roll by a line of stitches 13. The free edge of the flap 11 is preferably secured to the longitudinal frame 1, as by means of tacks 100 14. A suitable amount of cushion material, or padding 15 is introduced between the flaps 11 and 12, this padding preferably being extended over the edge-roll and along

the edge of the spring structure. The free edge of the skirt or marginal flap 12 is preferably secured to the bottom of the frame 1, as by means of tacks 16.

5 By means of the improved construction, it is possible to provide an upholstery spring structure with a "spring edge" which presents a straight and uniform appearance. This may be done without the use of highly 10 skilled labor, and it may be done more expeditiously and more cheaply than has heretofore been possible.

15 The edge-roll D may be pre-formed of any suitable material. It may comprise a rope of any suitable material, or, as in the preferred construction, it may comprise a closely wound small roll of paper, or a roll formed by twisting a strip or strips of paper so as to form a member of practically circular cross section.

20 The foregoing detailed description has been given for clearance of understanding only and no unnecessary limitations should be understood therefrom, but the appended 25 claims should be construed as broadly as permissible in view of the prior art.

What I regard as new and desire to secure by Letters Patent, is:

1. The combination of a frame, a row of 30 upholstery springs mounted thereon, a marginal wire adjacent the end-rings of said springs, an edge-roll adjacent said marginal wire, and clips securing said wire and edge-roll together and to said end-rings, 35 each of said clips having short arms clinched about an end-ring and the marginal wire and having a long arm forming a ring encircling and gripping said edge-roll, said clips being disposed wholly at the outer portions of said 40 end-rings and having connections with the end-rings only at said outer portions.

2. The combination of a frame, a row of 45 upholstery springs mounted thereon, a marginal wire adjacent the end-rings of said springs, an edge-roll adjacent and disposed above said marginal wire, and clips securing 50 said wire and edge-roll together and to said end-rings, each clip comprising a metal strip having its end portions equipped with short arms clinched upon a marginal wire and an end-ring, and a central long arm forming a ring encircling and gripping the

superposed edge-roll, said clips being disposed wholly at the outer portions of said end-rings and having connections with the 55 end-rings only at said outer portions.

3. The combination of a frame, a row of upholstery springs mounted thereon, a marginal wire adjacent the end-rings of said springs, clips, each comprising a metal strip superposed above the marginal wire and the adjacent portion of an end-ring and having short arms turned downwardly and clinched beneath the marginal wire and end-ring, an edge-roll disposed over the marginal wire and adjacent portions of the end-rings, and arms formed integrally with said clips and curved to embrace and grip the edge-roll superposed above the clips, said clips being disposed wholly at the outer portions of said end-rings and having connections with the 60 end-rings only at said outer portions.

4. A clip adapted to be supported wholly on the outer portion of an end-ring and to support a marginal wire and a superposed edge-roll, comprising a body-portion equipped with short arms adapted to be clinched about an end-ring of a spring and a marginal wire disposed adjacent said end-ring and equipped also with a long arm adapted to be clinched 70 upon an edge-roll.

5. A clip adapted to be supported wholly on the outer portion of an end-ring and to support a marginal wire and a superposed edge-roll, comprising a sheet-metal member having a body-portion equipped at each end with oppositely extending short arms and equipped intermediately with a long arm.

6. A sheet metal clip adapted to be supported wholly on the outer portion of an end-ring and to support a marginal wire and a superposed edge-roll, comprising a body portion equipped with two pairs of oppositely disposed short arms adapted to be clinched about the end-ring of a spring and the marginal wire disposed adjacent said end-ring, an intermediate short arm adapted to be clinched about said end-ring at a point where said ring abuts said marginal wire, and a long arm opposite said intermediate short arm adapted to support an edge-roll 80 above said marginal wire.

CHARLES R. HULTGREN.
